P. BECKER

WINDOW CONSTRUCTION

Filed March 13, 1922

UNITED STATES PATENT OFFICE.

PAUL BECKER, OF EAST CLEVELAND, OHIO.

WINDOW CONSTRUCTION.

Application filed March 13, 1922. Serial No. 543,232.

To all whom it may concern:

Be it known that I, PAUL BECKER, a citizen of the United States, residing at East Cleveland, in the county of Cuyahoga and State of Ohio, have invented a certain new and useful Improvement in Window Constructions, of which the following is a full, clear, and exact description.

This invention relates to a window construction for buildings.

The principal object of the invention is to provide a window construction wherein both the upper and lower sashes may be readily removed when desired for cleaning or for any other purpose. Further the invention aims to accomplish the above result with what may be termed a weightless sash, that is to say, one which can be easily raised and lowered, and which will stay at a given position without the necessity for the usual ropes and counterbalancing sash weights.

In the accompanying sheet of drawings, Fig. 1 is a perspective view of a window construction embodying my invention, the lower sash being removed and two molding pieces which respectively form portions of the guideways for the upper and lower sashes being shown by dotted lines out of their normal positions to illustrate the manner in which they may be swung to permit the removal of the upper and lower sashes; likewise in this view one of the weather strips for the lower sash is shown by dotted lines to illustrate its removability to permit the removal of the lower sash; Fig. 2 is a vertical sectional view of the same showing by dotted lines the upper and lower sashes; Fig. 3 is a perspective view of one of the sashes removed from the frame; Fig. 4 is a transverse sectional view substantially along the line 4-4 of Fig. 2; Fig. 5 is a detailed sectional view showing the weather stripping and the anti-friction bearings with which the sashes of the window may be provided on one or both sides; Fig. 6 shows a perspective view of one of the so-called anti-friction bearings; Fig. 7 is a detailed sectional view illustrating the manner in which the weather stripping is fitted into the window frame so that the projecting portions thereof will fit into the vertical slots in the window sashes; and Fig. 8 shows one of the two removable

sections of the weather stripping removed from the frame.

Referring now to the drawings, 10 represents the window frame, and 11 and 12 the upper and lower sashes which are adapted to be moved up and down in vertical guideways at the sides of the frame 10.

As the present invention contemplates the removability of the sashes from the frame 10, the usual sash weights and cords are eliminated, and in order that the sashes may be readily raised and lowered and will nevertheless remain in a position to which they may be moved, anti-friction rollers are provided at one or both sides of each sash, but preferably on one side only. Although ball bearings have been used by me very effectively, I prefer to employ cylindrical bearings 13, and to mount each of these bearings in a bifurcated end of a holder 14 in the form of a metal stamping provided with a shank which is fitted and held friction tight in openings provided in the vertical edge of the sash. Any number of these rollers may be provided along the side of the sash, but in this instance two are shown. These rollers are adapted to engage the opposing wall of the runway of the frame 10 directly opposite the sash, and they are preferably pressed yielding against the runway by spring means which in this instance is provided at the opposite side of the sash and is here shown to consist of a flat leaf spring 15, which is secured at one end to the sash and extends lengthwise of the sash. This leaf spring is bowed outwardly as best shown in Fig. 3, and it provides just enough friction to hold the sash in any position to which it may be raised or lowered, but still it permits the sash to be moved quite readily.

To provide a construction which is substantially draft and dust tight, weather stripping is provided for the sides and bottom of the lower sash, and for the sides and top of the upper sash. This weather stripping is in the form of flat metal strips 16 the vertical ones of which fit into slots in the window frame and project outwardly from the slots into companion slots 17 provided in the window sashes alongside the rollers 13 and springs 15. For the lower sash there is a weather strip which extends across the bottom of the frame, and two vertical strips which extend up along the sides

of the frame for substantially but little less than the height of the sash. At their lower ends the side strips 16 rest upon the bottom strip 16. For the upper sash there is an upper strip 16 extending in a slot across the top of the window frame and two vertical strips which extend down along the runway for the upper sash for substantially but a trifle less than the full length of the sash.

In order that the sashes may be removed from the window frame, the vertical weather strips 16 along one side of the frame for both sashes are removable from the slots which normally receive them. Should it be desired to remove the removable strip for the lower sash, the latter is slid up to the top of the frame, whereupon the weather strip can be lifted out of place. Likewise, should it be desired to remove the removable strip for the upper sash, the latter is moved downwardly in the frame to the bottom thereof, whereupon the removable section of the weather stripping can be lifted out of place. The slots 17^a of the frame which receive the removable vertical weather strips 16 are of the same length as these strips so that the latter are not moved up or down when the sashes are raised or lowered.

To permit the sashes to be removed not only is it essential that the weather strips along one side of the frame be removable, but it is essential also that the molding strips or portions thereof which constitute the front guide walls for the upper and lower sashes be readily removable, or movable to positions such as to enable the upper and lower sashes to be swung inward and lifted bodily from the frame. This last mentioned feature is attained by, and constitutes an important part of the present invention.

In accordance with the present invention the molding strip 18 which constitutes the front guideway for the lower sash at that side where the removable weather strips are arranged, is not permanently fastened in its normal position, but at its upper end is hinged or pivoted by a screw 19 or equivalent device, the pivotal axis being in a direction crosswise of the jamb so that this molding strip can be swung inward into the room. At its lower end adjacent the bottom of the frame, this strip is held in place by a sliding latch 20 having a part which is adapted to project across the bottom of this molding strip, as indicated in Fig. 1, but when the latch is pulled back the molding strip can be swung into the room. Likewise a section 21 of the molding strip which forms the front or inner wall of the guideway for the upper sash at that side thereof where the removable weather strips are arranged, is pivoted to the window frame at 22 so that it also can be swung inward in

the manner indicated by dotted lines in Figs. 1 and 2 provided the lower window is removed. It is not essential that the lower end of this molding section 21 be fastened in place for normally the sashes hold it in 70 normal position notwithstanding the fact that it is pivoted to swing in the manner just stated.

Ordinarily the molding strip 18 and the molding strip section 21 are vertical and function in the ordinary manner like fixed molding strips, as indicated by full lines in Fig. 1. The sashes can now be moved up and down in the usual manner, and will stay where placed, notwithstanding the fact that 80 sash weights are not connected to them.

Should it be desired to remove the lower sash to clean it, or for some other purpose, this sash is elevated so that it extends opposite the upper sash; then the removable weather stripping section 16 is slipped out of place; then the molding strip 18 is swung inwardly, i.e. away from the frame; and then the sash may be lowered to its normal position and then swung inward at the side 90 where the removable weather stripping and movable molding strip are normally located, and then lifted out of place. To restore it, the sash is put back into the frame and is slid up to the topmost position; then the removable section of the weather strip is put back into place, the sash is lowered, and the molding strip 18 is swung downward to normal position and locked with the latch 20.

Should it be desired to remove the upper 100 sash, the lower sash is first removed in the manner just explained; then the upper sash is slid downward to the bottom of the window frame and the removable weather strip section is slipped out of place; then the section 21 of the molding is swung inward; then the sash is elevated somewhat so as to come opposite the opening provided by the swinging of the section 21 of the molding, and then is swung inward at the side where the 110 removable weather strip and swinging molding strip are normally arranged, and then lifted bodily out of place.

Thus it will be seen that the objects stated at the beginning of the specification are accomplished in a very effective manner by the present invention.

Having described my invention, I claim:

1. In a window construction, a window frame having upper and lower sashes slideable vertically in guideways formed by the frame, weather stripping carried by the frame and engaged by said sashes, sections of the weather stripping engaged by upright portions of the sashes on one side of the frame being removable, and said frame having on the side upon which the removable weather stripping is mounted molding strips with movable portions normally forming the inner walls of the upright guideways 130

for the sashes and permitting the removal of the sashes when the removable sections of the weather stripping are removed, said sashes being movable laterally sufficiently to 5 permit the side freed from the weather stripping and molding strips to be swung inwardly.

2. In a window construction, a window frame having a pair of sashes movable up and down in vertical guideways of the frame, one in a plane at the rear of the other, said frame having slots receiving weather stripping, and the sashes having slots into which portions of said weather 10 stripping extend, one upright section normally engaged by the lower sash being removable from the frame when the lower sash is elevated to the top thereof, and one upright section of the weather stripping 15 on the same side of the frame normally engaged by the upper sash being removable from the frame when the upper sash is lowered to the bottom of the frame, and said frame having molding strips constituting inner guide walls for the sashes on the side of the frame having the removable weather 20 stripping, portions of said strips being pivoted to swing inward so as to permit the removal of the sashes when the removable sections of the weather stripping are removed, said sashes being movable laterally in the frame sufficiently to permit the side freed 25 from the weather stripping and molding strips to be swung inwardly.

3. In a window construction, a window frame having a pair of sashes movable up and down in vertical guideways of the frame, one in a plane at the rear of the other, said frame having slots receiving 30 weather stripping, and the sashes having slots into which portions of said weather stripping extend, one upright section normally engaged by the lower sash being removable from the frame when the lower sash 35 is elevated to the top thereof, and one upright section of the weather stripping on

the same side of the frame normally engaged by the upper sash being removable from the frame when the upper sash is lowered to the bottom of the frame, and said 50 frame having molding strips constituting inner guide walls for the sashes on the side of the frame having the removable weather stripping, portions of said strips being pivoted to swing inward so as to permit the removal of the sashes when the removable sections of the weather stripping are removed, said sashes being movable laterally in the frame sufficiently to permit the side freed 55 from the weather stripping and molding strips to be swung inwardly.

4. In a window construction, a window frame having a sash slidable therein, weather stripping for the sash comprising a section extending across the end of the frame 60 and two upright sections extending vertically along the sides of the frame for substantially the height of the sash, said weather stripping being in the form of flat strips located in slots of the window frame, and the sash having slots into which said strips normally extend, one of the strips along one of the sides of the sash being readily removable from the slot of the frame when the sash is moved along the frame for substantially its 65 height away from normal position, and said frame having a molding which normally retains the sash in the frame and constitutes part of the guideway therefor, a portion of the molding located opposite said removable 70 section of the weather stripping being movable from normal position so as to permit the sash to be swung inward and lifted out of place when the removable section of the weather stripping is removed, said sash being yieldably supported in the frame whereby it is movable laterally to permit the side freed from the weather stripping and molding 75 to be swung inwardly.

In testimony whereof, I hereunto affix my 80 signature.

PAUL BECKER.
